Gustav A. Bisler, Inventor
by Alexander Haubruck, Attorney

UNITED STATES PATENT OFFICE.

GUSTAV A. BISLER, OF PHILADELPHIA, PENNSYLVANIA.

DESIGN FOR A BOX-LID.

SPECIFICATION forming part of Design No. 29,172, dated August 9, 1898.

Application filed May 9, 1898. Serial No. 680,225. Term of patent 3½ years.

To all whom it may concern:

Be it known that I, GUSTAV A. BISLER, a citizen of the United States, residing in the city and county of Philadelphia, State of Pennsylvania, have invented and produced a new and original Design for the Lid of a Box, of which the following is a specification, reference being had to the accompanying drawing, forming part thereof.

5 The leading feature of my design for the lid of a box is a lid having a body of conoidal form, a cylindrical neck, and a bead intermediate of said body and neck, the face of said bead being outside of the plane of the face of said neck.

The figure represents a perspective view of a box-lid embodying my design.

In the drawing, A designates the lid of a box, the same having a conoidal body B, a cylindrical neck C, and a bead D, the latter being intermediate of said body and neck and having its face outside of the plane of the face of said neck. 20

Having thus described my invention, what I claim as new, and desire to secure by Letters 25 Patent, is—

The design for the lid of a box, substantially as described and shown.

GUSTAV A. BISLER.
